(57) **CLAIM**

The ornamental design for a locking handle for range drawers, substantially as shown and described above.

DESCRIPTION

FIG. 1 shows a front, elevation view of a locking handle for range drawers embodying the present invention. The configuration of the top, bottom, sides, and back of the locking handle for range drawers form no portion of the claimed design.

The characteristic feature of the design resides in the asymmetric flat on a symmetrical combination of a rounded shape, extending from connection with a rectangle having rounded corners.

The present invention comprises the design for rotatable handles which can be used to prevent drawers from leaving open positions, such as a slideable drawer containing a cooking range connectable to a source of propane, mounted on the exterior of a recreational vehicle.

The broken line orientation of a drawer edge with respect to the claimed locking handle for range drawers, is for purposes of representing the environment only and form no part of the claimed design.
